COMBINED FIREPLACE GRATE AND LOG HOLDER

Robert T. Schmitt, 517 Johnson Road NW,
Grand Rapids, Mich. 49504

Filed May 27, 1971, Ser. No. 147,727

Term of patent 14 years

Int. Cl. D23—03

U.S. Cl. D23—98

FIG. 1 is a perspective view of a combined fireplace grate and log holder showing my new design;

FIG. 2 is a side elevational view thereof;

FIG. 3 is an end elevational view thereof;

FIG. 4 is a top plan view thereof;

FIG. 5 is a bottom plan view thereof.

I claim:

The ornamental design for a combined fireplace grate and log holder, as shown.
